Primary Examiner — John R Yeh

(57) **CLAIM**

The ornamental design for a toy kitchen, as shown and described.

DESCRIPTION

1. Toy kitchen

1.1 : Perspective

1.2 : Perspective

1.3 : Front

1.4 : Back

1.5 : Left

1.6 : Right

1.7 : Top

1.8 : Bottom

1.9 : Enlarged

1.10 : Enlarged

1.11 : Perspective

The parts shown by means of broken lines in the reproductions are not part of the claimed design; fig. 1.9, 1.10 are the enlarged views of the portion taken at line 9, line 10 in fig. 1.1; the dash dot dash lines in fig. 1.1, 1.9, 1.10 and the label "9", "10" in fig. 1.1 are for the purpose of depicting the cut line of the enlarged view and form no part of the claim.

1 Claim, 11 Drawing Sheets
